FLEXIBLE BAG FOR LIQUID STORAGE

Kenneth D. Sears, Box 225, West Yellowstone,
Mont. 59758

Filed Apr. 15, 1971, Ser. No. 134,546

Term of patent 14 years

Int. Cl. D9—02; D24—04

U.S. Cl. D9—182

FIG. 1

FIG. 2

FIG. 3

FIG. 4

FIG. 5

FIG. 1 is a view in side elevation of a flexible bag for liquid storage, showing my new design, the side opposite that shown being substantially a mirror image thereof;

FIG. 2 is a view in front elevation thereof;

FIG. 3 is a view in rear elevation thereof;

FIG. 4 is a view in top plan thereof; and

FIG. 5 is a view in bottom plan thereof.

I claim:

The ornamental design for a flexible bag for liquid storage, substantially as shown and described.
